UNITED STATES PATENT OFFICE.

JESSE W. SILVER, OF SOUTH TACOMA, WASHINGTON, ASSIGNOR TO WILLIAM J. JEFFRIES, OF TACOMA, WASHINGTON.

CARBON-REMOVING AND LUBRICATING ATTACHMENT FOR INTERNAL-COMBUSTION ENGINES.

1,325,381.

Specification of Letters Patent.

Patented Dec. 16, 1919.

Application filed April 10, 1919. Serial No. 289,007.

To all whom it may concern:

Be it known that I, JESSE W. SILVER, a citizen of the United States, residing at South Tacoma, in the county of Pierce and State of Washington, have invented new and useful Improvements in Carbon-Removing and Lubricating Attachments for Internal-Combustion Engines, of which the following is a specification.

This invention relates to means for improving the operation of internal combustion engines by supplying thereto a carbon removing and lubricating vapor and thereby cleaning the cylinders of gasolene or analogous internal combustion engines or motors and materially economizing in the use of gas in the operation of the engine or motor. One of the principal objects of the invention is to provide an attachment that may be readily applied to gasolene engines of automobiles or other vehicles and also to stationary gas engines without requiring any essential modification in the construction and arrangement of the parts of the engine and whereby a cleaning and lubricating vapor may be automatically supplied to the manifold of a gasolene or internal combustion engine and distributed throughout the series of cylinders comprised within the engine structure. With this and other objects and advantages in view, the invention consists of the construction and arrangement of the several parts which will be more fully hereinafter described and claimed.

In the drawings:

Figure 1 is an elevation of a portion of an internal combustion engine of the type usually employed in automobiles and showing intake and exhaust manifolds and a part of the dash of an automobile with the improved attachment applied thereto, and mainly shown in transverse vertical section.

Fig. 2 is a transverse vertical section taken in the plane of the line 2—2, Fig. 1.

Fig. 3 is an enlarged horizontal section taken in the plane of the line 3—3, Fig. 1.

The numeral 5 designates a container which is preferably formed of glass and supported by a band or clip 6 which is clamped around the said container and secured to the dash 7 by a suitable fastening means, as at 8. The band or clip 6 will be first secured to the dash and the container 5 subsequently

inserted therein and secured, the said clip 55 having angularly projecting ends 9 engaged by a clamp screw 10 whereby the said ends 9 may be drawn closely together to clamp the band or clip around the body of the container and reliably hold the latter in applied position. The container 5 has an upper reduced neck 11 which is corrugated or threaded to receive a chamber cap 12 and a horizontal partition plate or disk 13 which is firmly held in place on the upper end of 60 the said neck within the lower portion of the chamber cap 12. The partition disk 13 practically forms a bottom for the chamber cap 12 and has a central depending tube 14 with a perforated flanged disk 15 at its 65 lower end. On the tube 14 a short distance below the partition disk 13 is a perforated flanged disk 16 similar to the disk 15. The tube 14 with the disks 15 and 16 and the partition disk 13, as well as the chamber 70 cap 12, are all formed of metal or other suitable material of a non-corrosive nature, and within the chamber cap 12 is a mixing chamber 17 of materially less diameter than the cap and whereby a passage 18 is formed 75 between the mixing chamber and the cap, the passage 18 being obstructed in its complete continuity by depending flange 19 extending from one vertical wall of the chamber 17 downwardly to the partition disk 13. 80 From the bottom of the mixing chamber a short length tube 20 extends and continuous through the partition disk 13, said tube terminating above the perforated flanged disk 16. The chamber cap 12 has a top 85 inlet 21 with a removable cover 22 fitted thereover for filling purposes. Connected to the upper portion of the mixing chamber 17 is a tube or pipe 23 which extends through or across the passage 18 and outwardly 90 through the adjacent wall of the chamber cap 12 and in part lies along and close to the exhaust manifold and is also connected to the intake manifold 24 as at 25, the pipe 23 having a valve 26 therein adjacent its 95 point of attachment to the intake manifold for controlling communication of the mixing chamber 17 with the said manifold. Attached to and opening through the chamber cap 12 and communicating with the passage 100 18 just above the obstructing or baffle flange 19 is a pipe 27 which extends along in engagement with the exhaust manifold 28,

The container 5 is first filled to about two-thirds of its capacity with kerosene or coal oil and a suitable proportion of lubricating oil, the mixture of coal oil and lubricating oil being first prepared before depositing the same in the container. This combination of oils is supplied through the inlet 21 and passes downwardly through the chamber cap 12 to the upper end of the pipe 14 and then through the latter into the container and after the container has thus been supplied with the combined oils, the motor or engine, of which the manifolds 24 and 28 form parts, is started into operation and gradually slowed down, the valve 26 being closed when the motor or engine is started. After the motor or engine has been suitably slowed down, or its running speed materially reduced, the valve 26 is opened and the suction of the motor or engine is permitted to operate through the pipe 23. This suction of the engine or motor acting through the pipe 23 draws the air out of the mixing chamber 17 and causes the formation of a partial vacuum in the said chamber and creates a suction through the tube 20 relative to the contents of the container 5 and the outside air at the same time is drawn through the pipe 27 into the passage 18, this air, as will be understood, being heated. The hot air drawn into the passage way 18 through the pipe 27 is forced to pass upwardly over and down around the mixing chamber 17 by reason of the baffle or obstructing flange 19 and by this means the said mixing chamber is thoroughly heated. The heated air from the passage 18 continues downwardly through the pipe 14 and is delivered close to the bottom of the container 5 and then passes upwardly through the lower flanged perforated disk 15 which operates to divide the air into minute currents. These currents of heated air are drawn upwardly through the combined oils in the container 5 which causes the said combined oils to evaporate. The air currents laden with the vaporized oils then pass upwardly through the perforated disk 16, the latter acting as a splash disk to prevent the air from throwing the oil in bulk upwardly into the mixing chamber 17. After passing through the perforated disk 16 the oil laden hot air currents then enter the said mixing chamber through the tube 20 which is materially heated and effects a thorough mixture of the air and oils. From the mixing chamber the vaporized oils and the air pass out through the pipe 23 and are further heated and more completely vaporized by the heated part of this pipe and then conducted down to the intake manifold 24 which still further heats the mixture and creates a gas which unites with the gasoline gas after the latter has passed through the usual form of carburetor, and at the same

time a greasy lubricant is carried into the cylinders and caused to engage the pistons of the motor or engine with said gasoline gas and by this means in combination with the usual lubricating or oiling system, the 70 pistons are thoroughly lubricated. The vaporized coal or kerosene oil that is carried into the manifold with the hot air and mixed with the gasoline gas serves as a cylinder cleaning medium and also as an effective de-carbonizing agent and whereby the carbon deposits within the cylinders and adjacent parts are removed and caused to pass out through the exhaust. The cleaning or de-carbonizing element also serves to keep the 75 spark plug heads in cleanly condition with material advantage in the operation of the same. In addition to removing the carbon from the cylinder walls, it will also be understood that the pistons are relieved of car. 80 bon deposits. The pipe 27 is held in connection with the exhaust manifold as shown by means of a suitable clamp 29, and the heat of this exhaust manifold is transmitted to the pipe and the air drawn through the latter 85 is correspondingly tempered or heated.

From the foregoing it will be seen that the improved attachment may be readily applied to any type of automobile or other vehicle motor or engine by simply securing the 95 band or clip 6 to a support at a suitable distance from the intake and exhaust manifolds and connecting up the pipe 23 to the intake manifold and securing the pipe 27 against the exhaust manifold. It will also 100 be understood that the container 5 will have a sufficient capacity to render the operation thereof effective and it is proposed to modify the proportions, dimensions and general details of construction within the scope of 105 the appended claims to adapt the improved attachment for various applications.

I claim:—

1. In a carbon removing and lubricating attachment of the class specified, a container 110 for oils, a chamber cap on and having communication with the container and provided with an inlet means, a mixing chamber within the cap in communication with the container, a passage way being formed between the walls of the cap and mixing chamber, the mixing chamber being closed with relation to said passage way, a hot air pipe connected to the cap and opening into said passage way, and an outlet pipe connected 115 to and communicating with the mixing chamber.

2. In a carbon removing and lubricating attachment of the class specified, a container 120 for oils, a chamber cap on and having communication with the container and provided with an inlet means, a partition on the upper portion of the container having a depending tube terminating near the bottom of the container and also opening into the 125

cap, a mixing chamber within the cap and of smaller dimensions than the latter to provide a passage way around the mixing chamber, the mixing chamber having bottom communication with the upper portion of the container and the continuity of the passage way obstructed adjacent to said bottom communication, a hot air pipe connected to and opening into the said passage way, and a vapor outlet pipe connected to and opening into the mixing chamber.

3. In a carbon removing and lubricating attachment of the class specified, a container for oils, a chamber cap on and having communication with the container and provided with an inlet means, a partition on the upper portion of the container having a depending tube terminating near the bottom of the container and also opening into the cap, said depending tube having a lower perforated disk thereon, a mixing chamber within the cap and of smaller dimensions than the latter to provide a passage way around the mixing chamber, the mixing chamber having bottom communication with the upper portion of the container and the continuity of the passage way obstructed adjacent to said bottom communication, a hot air pipe connected to and opening into the said passage way, and a vapor outlet pipe connected to and opening into the mixing chamber.

4. In a carbon removing and lubricating attachment of the class specified, a container for oils, a chamber cap on and having communication with the container and provided with an inlet means, a partition on the

upper portion of the container having a depending tube terminating near the bottom of the container and also opening into the cap, said depending tube having lower and upper 40 perforated flanged disks thereon, a mixing chamber within the cap and of smaller dimensions than the latter to provide a passage way around the mixing chamber, the mixing chamber having bottom communication 45 with the upper portion of the container and the continuity of the passage way obstructed adjacent to said bottom communication, a hot air pipe connected to and opening into the said passage way, and a vapor outlet pipe connected to and opening into the mixing chamber.

5. In a carbon removing and lubricating attachment of the class specified, the combination with the gas inlet and the exhaust 55 manifolds of an internal combustion motor, of a container for oils supported adjacent to the manifolds, a chamber cap on and having communication with the container and provided with an oil inlet means, a mixing 60 chamber having closed walls and located within the cap, a passage way being formed between the walls of the cap and mixing chamber, a hot air pipe secured on and heated by the exhaust manifold and connected 65 to and opening into the said passage way, and a valved vapor outlet pipe connected to and opening into the mixing chamber and also connected to the gas inlet manifold.

In testimony whereof I have hereunto set 70 my hand.

JESSE W. SILVER.

It is hereby certified that Letters Patent No. 1,325,381, granted December 16, 1919, upon the application of Jesse W. Silver, of South Tacoma, Washington, for an improvement in "Carbon-Removing and Lubricating Attachments for Internal-Combustion Engines," were erroneously issued to William J. Jeffries, as assignee of the entire interest in said invention, whereas said Letters Patent should have been issued to the inventor, said *Silver*, and *William J. Jeffries*, said Jeffries being assignee of *one-half* interest only in said invention, as shown by the record of assignments in this office; and that the said Letters Patent should be read with this correction therein that the same may conform to the record of the case in the Patent Office.

Signed and sealed this 17th day of February, A. D., 1920.
